ASSIGNORS TO SIEMENS & HALSKE AKTIENGESELLSCHAFT, OF WERNERWERK,
SIEMENSSTADT, NEAR BERLIN, GERMANY

TELEPHONE SYSTEM

Application filed October 9, 1926, Serial No. 140,448, and in Germany October 22, 1925. Renewed May 20, 1929.

This invention relates to telephone systems in general but more particularly to circuit arrangements for enabling complete symmetry to be obtained under all conditions of 5 automatic signalling (calling, speaking condition, clearing signal, subscriber's flashing signal), this being irrespective of whether the need for symmetry in the lines is due to the lines being used for phantom circuits or 10 because they have to be protected from induced currents (railway currents, etc.).

According to the invention, the automatic transmission of signals can be achieved for 15 example in that when the plug is inserted 13 into the jack of the trunk line at the telephone exchange A for the purpose of initiating a call, an alternating current is sent from the exchange A to the exchange B and, on being received thereat, special known switching 20 means cause the calling lamp to light. When at the exchange A the plug is withdrawn from the jack of the trunk line, for example at the end of the conversation, a further current impulse goes to the exchange B and extinguishes the supervisory lamp thereat. For 25 transmitting signals from the subscriber to the exchange A, alternating currents are sent from the exchange B to the exchange A for operating the supervisory lamp at the exchange A, the condition thereof depending 30 on whether the receiver is lifted or replaced at the subscriber's instrument. Alternately the problem of automatically sending signals 35 direct over trunk lines, which are isolated by repeaters, can be solved by signalling from the exchange A to the exchange B in the manner described above, and by signalling from the exchange B to the exchange A by 40 transmitting the particular maintained condition with the assistance of an alternating current of a frequency different from that used for the alternating current from the exchange A to the exchange B. Another 45 solution of this problem consists in transmitting a direct current impulse from the exchange A to the exchange B and an alternating current impulse from the exchange B to the exchange A.

50 The drawings, comprising Figs. 1-3, in-

clusive, show by way of example several arrangements of the circuit.

Figure 1 shows a trunk line connecting two telephone exchanges A and B, in which signalling from A to B and vice versa is effected 55 by means of alternating current impulses;

Figure 2 shows a circuit arrangement, in which the signalling from the telephone exchange A' to B' is effected by means of alternating current impulses, and in the opposite 60 direction it is effected by maintained alternating current of a different frequency, for example audible frequency.

Figure 3 shows a circuit arrangement, in which the signalling from the telephone exchange A'' to B'' is effected by direct current impulses, and from B'' to A'' by maintained 65 alternating current.

A detailed description of the invention may now be given. Referring to Figure 1, 70 when the operator at the position KA plugs into the junction line, the supervisory lamp in the cord (not shown) is lighted and the relay C is energized by its winding I over the contact k11 and the c-lead over the plug: 75

1. Earth over the plug inserted in the jack Kv, back contact k11, winding I of relay C, battery, earth.

The relay C with its contact c12 operates 80 the relay J:

2. Earth, back contact k11, front contact c12, relay J, battery, earth.

The relay J is operated; at its contact j1 it disconnects the relay R, and over the front contacts j2 and j3 and the repeater U1 it 85 sends ringing current to the line. Furthermore it energizes the relay KO and the winding II of the relay C over the back contacts k12 and k13:

3. Earth, winding II of relay C, back contact k13, front contact j4, back contact k12, relay KO, battery, earth.

Relay KO at contact k11 interrupts the circuit 2 for the relay J. The latter falls 95 back and the transmission of ringing current to the line ceases. The relay R is again connected to the line and the relay K1 is operated over the contact k12. The relay KO now locks itself in series with relay K1: 100

4. Earth, relay K1, double front contact k_{012} , relay KO, battery, earth.

After relay K1 has operated, the relay C locks itself over its winding I and its contact $c13$. At the position KB the relay R2 responds to the ringing current impulse sent out by the relay J at the position KA, and the relay R2 at its front contact $r21$ operates the relay U2:

10 5. Earth, back contact $u31$, front contact $r21$, back contact $u32$, relay U2, battery, earth.

When the relay R2 has been de-energized, (at the end of the ringing impulse sent by relay J at the position KA) the relay U2 locks itself over its contact $u21$ in series with relay U3, which is operated:

6. Earth, relay U3, double front contact $u21$, relay U2, battery, earth.

29 Relay U2 also closes the circuit of the supervisory lamp UL:

7. Earth, back contact $p1$, front contact $u22$, lamp UL, battery, earth.

The operator at the exchange B plugs into the wanted connection, thereby energizing the relay P, so that the supervisory lamp is again extinguished by the opening of the contact $p1$. When the wanted subscriber answers, the relays S1 and S2 are energized and the relay SO is energized by its winding I over the back contact $k31$:

8. Earth, front contacts $s11$, $s21$, back contact $k31$, winding I of relay SO, battery, earth.

8. The relay closes a circuit for the relay J2 over:

9. Earth, front contact $u23$, back contact $k21$, front contact $s01$, relay J2, battery, earth.

10. Relay J2 is operated. At contact $j21$ it disconnects the calling line R2 from the relay and over the contacts $j22$, $j23$ it sends ringing current over the repeater U2 to the line. Furthermore, at contact $j24$ the winding II of the relay SO is energized:

10. Earth, winding II of relay SO, back contact $k32$, front contact $j24$, contact $k35$, relay $k2$, battery, earth.

The relay J2 is now disconnected at the contact $k21$, and at contact $j22$ and $j23$ it interrupts the transmission of ringing current. At the contact $j21$ the relay R2 is again connected to the line and the relay K3 is operated in series with the relay K2:

11. Earth, relay K3, double front contact $k22$, relay K2, battery, earth.

The winding I of relay SO now locks the relay over its front contact $s02$ as follows:

12. Earth, front contact $s11$, $s21$ and $s02$, winding I of relay SO, battery, earth.

At the exchange A the relay R is operated by the impulse of ringing current sent from the exchange B, and the relay R connects up the relays UO and U1 at the exchange A in the same manner as the relay R2 at the ex-

change B. Thereupon the relay UO at its contact $u01$ applies earth to the a lead and so in known manner extinguishes the supervisory lamp in the cord circuit of the operator. At the end of the conversation when the subscriber hangs up his receiver, current is removed from the relays S1 and S2, and the relay SO in circuit 12 is also de-energized. The relay K2 being now energized, the relay J2 is operated over the back contact of $s03$:

13. Earth, front contacts $u23$ and $k23$, back contact $s03$, relay J2, battery, earth.

The relay R2 is again disconnected from the line and ringing current goes to the line over the repeater U2. The operation of the relay J2 also short circuits the relay K2, which therefore falls back:

14. Earth, battery, resistance SW3, front contacts $k33$ and $j24$, double front contact $k22$, relay K2, battery, earth.

During the impulse transmission the relay K3 holds itself over its own contacts and the contact $j24$.

Upon falling back, the relay K2 at its contact $k23$ opens the circuit of the relay J2, which then falls back. The transmission of ringing current is ended and the relay R2 is again connected to the line.

After the release of the relay J2, the relay K3 is also released, which during impulse transmission locked itself over its own circuit:

14a. Earth, battery, resistance SW3, front contacts $k33$, $j24$ and $k34$, relay K3, earth.

The back contact $k31$ of the relay K3 shunts the front contact $s02$, hence the relay SO is again operated if in the meantime the subscriber has again taken down his receiver, and another impulse of ringing current can be sent to the exchange A. The impulse sent from the exchange B after the receiver has been hung up at the subscriber's instrument operates the relay R at the exchange A. The latter short circuits the relay UO. (See the short circuiting of K2 circuit 14). Relay UO falls back and at its contact $u01$ it removes earth from the a lead, thus in known manner causing the lighting of the supervisory lamp in the operator's cord circuit. The relay U1 during the current impulse locks itself over:

15. Earth, front contact $c14$, relay U1, front contacts $u12$, r and $u13$, resistance SW, battery, earth; and it only falls back after the impulse has ended (therefore after the release of the relay R).

The disconnect signal having been received, the operator at the exchange A withdraws the plug from the jack Kv , thereby causing the release of the relay C. As the relay KO is energized (circuit 4), the relay J is operated over the back contact $c11$ and the front contact $k011$. The relay J sends ringing current to the exchange B in exactly the same manner as previously when the junction line was seized, the relay R being discon-

nected. After relay J has operated, the relay K0 falls back slowly (owing to the short circuit) (see relay K2 in circuit 14) and at contact k_{011} it opens the circuit 2 of the relay J. Upon the release of the relay J, ringing current is disconnected from the line, and the relay K1 is de-energized; during the impulse transmission it locked itself over its own contact and contact j_4 , (see relay K3 in circuit 14a). Thus the winding I of the relay C is again connected to the jack Kv and it is again ready to initiate a fresh seizing impulse. The impulse transmitted by the withdrawal of the plug at the exchange A is received at the exchange B by the relay R2, which de-energizes the relay U2 by short circuiting it. The relay U2 was energized in series with the relay U1 (circuit 6):

16. Earth, battery, resistance SW2, front contacts u_{33} , r_{21} , double front contact u_{21} , relay U2, battery, earth.

The supervisory lamp UL is lighted over the following circuit:

17. Earth, front contact p_2 , back contact u_{24} , lamp UL, battery, earth. The circuit 13 of the impulse relay J2 is opened at the contact u_{23} .

At the end of the impulse (relay R2 released) the relay U3 falls back. The relays U2 and U3 are ready to receive another seizing impulse. The operator at the exchange B releases the connection by withdrawing the plug BS, whereupon the relay P falls back and extinguishes the lamp UL (circuit 17).

25. Referring now to Figure 2, which shows a second method for carrying out the object of the invention, when the operator at the exchange A' plugs into the jack Kv1 of the junction line, the supervisory lamp in her cord circuit is lighted in known manner and the relay R3 is operated:

18. Earth, over the plug and the jack Kv1, back contact c_{21} , relay R3, battery, earth.

Ringing current of 25 periods is then sent 45 to the exchange B'. Furthermore the relay C2 is energized over the contact r_{31} :

19. Earth, front contact r_{31} , relay C2, winding I, battery, earth.

The relay C2 by opening its contact c_{21} , disconnects the relay R3 from the jack Kv1 and locks itself over the front contact c_{22} :

20. Earth over the plug and jack Kv1, front contact c_{22} , winding II of relay C2, battery, earth.

25. The transmission of ringing current to the line is ended after the release of the relay R3. The relay R4 at the exchange B' was energized by the incoming ringing current. At its contact r_{41} it closes a circuit for the relay U4:

21. Earth, back contact u_{51} , front contact r_{41} , back contact u_{52} , relay U4, battery, earth.

25. The relay closes the circuit of the super-

visory lamp, over which the lamp UL2 is lighted:

22. Earth, back contact p_{21} , front contact u_{42} , lamp UL2, relay K4, battery, earth. Furthermore, over the front contacts u_{43} , u_{44} , and the back contacts s_{31} , s_{32} as well as over the repeater U3 alternating current of 500 cycles is sent to the exchange A'.

At the end of the ringing current impulse from A', the relay R4 falls back (R4 does not respond to alternating current of 500 cycles). The relay U5 is now operated and locks itself in series with U4:

23. Earth, relay U5, double front contact u_{45} , relay U4, battery, earth.

The alternating current arriving at the exchange A' operates the relay T, thereby energizing the relay V over the contact t . The latter disconnects the line in order to prevent alternating current reaching the operator, and at the same time lights the supervisory lamp in the cord circuit by removing earth from the a lead.

When the operator at the exchange B' plugs into the wanted line, the relay P2 is 90 operated which, by opening the contact p_{21} , extinguishes the lamp UL2.

When the wanted subscriber answers, the relay S3 is energized and at its contacts s_{31} , s_{32} it disconnects the alternating current from the line. At its contact s_{33} , s_{34} the wanted subscriber's line is connected up. If alternating current fails, the relay T at the exchange A' falls back and so also releases the relay V, which here likewise switches 100 through the connection. At the same time the supervisory lamp in the operator's cord circuit at the exchange A' is extinguished.

At the end of the conversation, when the subscriber hangs up the receiver, the relay S3 is deenergized. The relay T at the exchange A' is operated by the alternating current coming from the exchange B' and it in turn operates the relay V, which at its contacts v_1 , v_2 , disconnects the line and sends 110 the clearing signal to the operator at the exchange A' over the contact v_3 . If the operator at the exchange A' now releases the connection by withdrawing the plug, the relay C2 falls back and the relay R3 is operated over the front contact v_4 of the relay V, which is still maintained energized:

24. Earth, front contact v_4 , back contact c_{23} , relay R3, battery, earth.

At its front contacts r_{32} , r_{33} , the relay 120 sends ringing current to the exchange B'. Furthermore the relay C2 is once more operated, owing to the operation of the relay R3:

25. Earth, front contact r_{31} , winding I of relay C2, battery, earth.

At its contact c_{23} the relay opens the circuit of the relay R3. Relay R3 falls back and cannot again be operated, because the relay V has also fallen back in the meantime. The ringing current arriving in the exchange B' 125

energizes the relay R4, which short circuits the relay U4:

26. Earth, battery, resistance SW4, front contact $u53$, and $r41$, double front contact $u45$, relay U4, battery, earth.

On falling back relay U4 disconnects at the contacts $u43$ and $u44$ alternating current from the line. The lamp UL2 is lighted:

27. Earth, front contact $p22$, back contact $u46$, lamp UL2, relay K4, battery, earth.

The relay U5 remains energized in the following circuit:

28. Earth, relay U5, front contacts $u54$, $r41$ and $u53$, resistance SW4, battery, earth.

15 At the end of the ringing impulse the relay R4 falls back and by opening the contact $r41$ it disconnects the relay U5. The operator at the position B' releases the connection by withdrawing the plug BS2, whereupon the relay P2 falls back and extinguishes the lamp UL2 by opening the contact $p22$.

Referring now to Figure 3, which shows the third method for accomplishing the object of the invention, when the operator at the exchange A'' inserts the plug into the jack Kv2 of the junction line, the relay R5 is operated:

29. Earth over the plug and jack Kv2, back contact $c31$, relay R5, battery, earth.

It closes its contacts $r51$ and $r52$, thereby 30 applying over the choke coils Dr1 and Dr2 an unearthing voltage of 60 volts to the windings of the repeater U4 connected to the a and b leads going to the exchange B''; hence the relay R6 is energized:

35 30. Positive pole of the battery, choke coil Dr2, front contact $r52$, repeater U4 winding I, b -lead, repeater 5 winding I, relay R6, repeater U5 winding II, a -lead, repeater U4 winding II, front contact $r51$, choke coil Dr1, 40 negative pole of the battery.

Furthermore the relay C3 was energized as follows:

31. Earth, front contact $r53$, winding I of relay C3, battery, earth.

45 It opens the circuit 27 at contact $c31$, and closes a locking circuit for itself at contact $c32$:

32. Earth over the plug and jack Kv2, front contact $c32$, winding II of relay C3, battery, earth.

The relay R5 falls back and opens its contacts $r51$ and $r52$. The voltage is thereby removed from the line and the windings I and II of the repeater U4 are connected together over the back contacts $r54$, $r55$. The relay R6 at the exchange B'' has been operated by the direct current voltage applied at the exchange A'' and has operated the relay U6:

50 33. Earth, back contact $u71$, front contact $r61$, back contact $u72$, relay U6, battery, earth.

Relay U6 is likewise operated and closes the following circuit for the supervisory lamp 55 UL3:

34. Earth, back contact $p31$, front contact $u61$, lamp UL3, relay K5, battery, earth.

The lamp UL3 is lighted. Furthermore ringing current is sent to the exchange A'' over the front contacts $u62$, $u63$ and the windings III and IV of the repeater U5:

70 35. Source of ringing current, front contact $u62$, back contact $s51$, windings III and IV of repeater U5, back contact $s52$, front contact $u63$, source of ringing current.

Voltage having been removed at the exchange A'' (by relay R5), the relay R6 falls back. (Relay R6 does not respond to ringing current). Hence relay U7 is operated and locks itself in series with relay U6:

75 36. Earth, relay U7, double front contact $u64$, relay U6, battery, earth.

The ringing current arriving in the exchange A'' operates the relay T2, which energizes the relay V2:

80 37. Earth, front contact $t21$, relay V2, battery, earth.

This at the contacts $v21$, $v22$, disconnects the line in order to prevent ringing current reaching the operator, and at the same time 90 lights the supervisory lamp in the cord circuit at the exchange A'' over the front contact $v23$.

When the operator at the exchange B'' 95 plugs into the wanted line, the relay P3 is operated, which extinguishes the lamp UL3 by opening the contact $p31$. When the wanted subscriber answers, the relay S5 is operated. At its contacts $s51$ and $s52$ it disconnects the ringing current from the line and at the contacts $s53$, $s54$ it switches through the wanted subscriber's line. If ringing current fails at the exchange A'' the relay T2 falls back and opens the circuit 37.

Hence the relay V2 also falls back. The 100 junction line is switched through at the contacts $v21$, $v22$, and at the same time the supervisory lamp is extinguished in the cord circuit of the operator at the exchange A''. 105

At the end of the conversation, when the 110 subscriber hangs up the receiver again, the relay S5 is de-energized; the relay T2 at the exchange A'' is operated by the ringing current arriving from the exchange B'' and it again energizes the relay V2, which severs the line in known manner and sends the clearing signal to the operator at the exchange A''. When the operator at the exchange A'' severs the connection by withdrawing the plug, the relay C3 falls back. 115 Relay R5 is operated over the front contact $v24$ of the still energized relay V2:

38. Earth, front contact $v24$, back contact $c33$, relay R5, battery, earth.

Relay R5 again applies voltage to the line 125 at the exchange B'' (circuit 30). Furthermore the relay C3 is again energized at the contact $r53$ (circuit 31) and at $c33$ it opens the circuit 36. The relay R5 falls back and cannot be again operated, because the relay 130

V2 has also fallen back in the meantime. The relay R6 at the exchange B'' has again been operated by the voltage (circuit 30) applied to the line at the exchange A''; at its contact *r61* it short circuits the relay U6. The latter falls back and disconnects ringing current from the line at the contacts *u62*, *u63*. The lamp UL3 is again lighted over the back contact *u65* and the front contact *p32*. The removal of voltage from the line at the exchange A'' (by R5) has caused relay R6 to fall back, the latter disconnecting the relay U7 as already described. The operator at the exchange B'' releases the connection by withdrawing the plug BS3, thereby causing the relay P to fall back, which at contact *p32* opens the circuit of lamp UL3 to extinguish it.

What is claimed is:

1. In a telephone system, a first and a second exchange, a trunk comprising inductively coupled sections extending between said exchanges, means at said first exchange for establishing a connection over said trunk, means responsive to said establishment for producing a momentary current flow of a certain character over said trunk, means at said second exchange responsive to said momentary current flow for operating a signal thereat and for producing a current flow of a different character over said trunk line to actuate a signal at said first exchange.
2. In a telephone system, a first and a second exchange, a trunk comprising inductively coupled sections extending between said exchanges, means at said first exchange for establishing a connection over said trunk, means responsive to said establishment for producing a momentary current flow of a certain character over said trunk, means at said second exchange responsive to said momentary current flow for operating a signal thereat and for producing a current flow of a different character over said trunk line to actuate a signal at said first exchange, means for extending said connection to a called party, and means operative when said called party responds for interrupting said current flow of a different character to de-actuate said signal at said first exchange.
3. In a telephone system, a trunk comprising incoming and outgoing sections, means responsive to the extension of a connection over one of said sections for sending a momentary impulse of current to the other section, means responsive to the extension of a connection over the other section for continuously transmitting current impulses to the first section, and signalling means at each section responsive to impulses transmitted from the other section.
4. In a telephone system, a trunk comprising incoming and outgoing inductively coupled sections, means for momentarily transmitting current of like characteristics from

one section to the other responsive to the establishment and to the breaking down of a connection over said one section, means for continuously transmitting current impulses of like characteristics from said other section to said first section responsive to the establishment and to the breaking down of a connection over said second section, and signalling means at each section operative responsive to the current transmitted from the other section.

5. In a telephone system comprising a trunk extending between two exchanges, a source of characteristic current at the first exchange, means responsive to the establishment of a connection with the trunk for momentarily connecting said current source to the trunk over a fixed current path, means responsive to the disestablishment of the connection with the trunk for momentarily reconnecting said current source to the trunk over the same circuit path previously used, and a signal at the second exchange operated responsive to each of said momentary connections.

6. In a telephone system comprising a trunk extending between two exchanges, a source of characteristic current at the first exchange, means for momentarily connecting said current source to the trunk responsive initially to the establishment of a connection with the trunk and subsequently to the disestablishment of the connection therefrom, a signal at the second exchange, and a single relay bridged across the trunk at the second exchange, said relay operating responsive to each of said momentary connections of the current source to actuate said signal.

7. In a telephone system comprising a trunk extending between two exchanges, means for extending a call from the first exchange to the second exchange via the trunk, means at the second exchange for further extending the call, means for answering the call, a source of characteristic current at each exchange, a supervisory circuit at the first exchange, a signal at the second exchange, means in the first exchange responsive to the establishment of a connection with the trunk for momentarily connecting the current source at the first exchange to the trunk over a fixed circuit means responsive to current from said source for actuating said signal, means responsive to the further extension of the call for deactuating said signal, means responsive to the answering of the call for connecting the current source at the second exchange to the trunk, means responsive to current from last said source for rendering said supervisory circuit effective, and means responsive to the disestablishment of the connection from the trunk at the first exchange for momentarily reconnecting first said current source to the trunk to reactivate said signal.

8. In a telephone system comprising a trunk extending between two exchanges, a source of characteristic current at the first exchange, a signal at the second exchange, means in the first exchange responsive to the establishment of a connection with the trunk for momentarily connecting the current source at the first exchange to the trunk over a fixed circuit means responsive to current from said source for actuating said signal, means responsive to the further extension of the call for deactuating said signal, means responsive to the answering of the call for connecting the current source at the second exchange to the trunk, means responsive to current from last said source for rendering said supervisory circuit effective, and means responsive to the disestablishment of the connection from the trunk at the first exchange for momentarily reconnecting first said current source to the trunk to reactivate said signal.

8. In a telephone system comprising a trunk extending between two exchanges, a source of characteristic current at the first exchange, means responsive to the establishment of a connection with the trunk for momentarily connecting said current source to the trunk over a fixed circuit, means responsive to the disestablishment of the connection from the trunk for reconnecting said current source to the trunk over the same circuit previously used, a signal at the second exchange, and a single relay bridged across the trunk at the second exchange, said relay operating responsive to each of said momentary connections of the current source to actuate said signal.

9. In a telephone system, a trunk comprising a plurality of inductively connected sections extending between two exchanges, means for extending a call from the first exchange to the second exchange via said trunk, means for answering the call, a source of alternating current in the second exchange, means responsive to the answering of the call for connecting said current source to the trunk, and means in the first exchange responsive to said alternating current for connecting a characteristic potential to a talking conductor of one section of said trunk.

10. The combination with a trunk comprising two talking conductors and a sleeve conductor terminating in a manual jack, of a relay normally connected to the sleeve conductor and operated responsive to the extension of a call to the trunk via the jack, a second relay controlled by the first relay, and means controlled by the second relay for connecting itself to the sleeve conductor in place of the first relay.

11. The combination with a trunk comprising two talking conductors and a sleeve conductor, of a ringing relay normally connected to the sleeve conductor and operated responsive to the extension of a call to the trunk, a holding relay energized initially responsive to the operation of the ringing relay, and means controlled by the holding relay when energized for locking itself to the sleeve conductor and for disconnecting the ringing relay therefrom.

12. In a telephone system, a trunk terminating in a manual jack, a relay normally connected to the sleeve of said jack, a second relay, means for operating said first relay when the trunk is connected with by way of said jack, means responsive to the operation of said first relay for applying ringing current to the trunk and for operating said second relay, and means responsive to the operation of said second relay for disconnecting said first relay from the sleeve of the jack and for connecting the second relay thereto.

13. In a telephone system, a trunk terminating in a manual jack, a relay normally connected to the sleeve of the jack, a second

relay, means responsive to the extension of a call to the trunk for applying a potential to the sleeve of the jack to operate said first relay, an energizing circuit for said second relay completed responsive to the operation of said first relay, and means responsive to the operation of said second relay for completing a locking circuit for itself including the sleeve of the jack and the potential thereon, and for disconnecting said first relay from the sleeve of the jack.

In witness whereof, I hereunto subscribe my name this 21st day of September, A. D. 1926.

WERNER SCHULZ.

In witness whereof, I hereunto subscribe my name this 21st day of September, A. D. 1926.

MAX FRISCHKE.

In witness whereof, I hereunto subscribe my name this 21st day of September, A. D. 1926.
